JAMES W. MARTIN, JR., OF TUCKAHOE, NEW YORK

HUMIDIFIER

Application filed May 26, 1936. Serial No. 111,709.

My present invention is embodied in a humidifier primarily intended for maintaining a desired amount of moisture in the air of living rooms, offices, factories, etc., and while 5 peculiarly adapted for use in combination with radiators of steam or hot water heating systems, it is well adapted for use wherever it is desirable to moisten atmosphere; also where liquids other than water are employed 10 as, for instance, disinfectants, perfumes, etc.

My humidifier includes means for continuously maintaining in moist or wet condition, a relatively large area of fibrous surface, preferably, in the form of a multiplicity 15 of travelling belts or endless bands of wick material which may be mounted on cooperating rollers, one of which is located so that the wick belts are carried below the level of water or other liquid in a tank, while the other is 20 above the level, preferably located so that the bands travel vertically. Preferably, there are two sets of such bands mounted on the same shaft-axes, but one set engages pulleys of smaller diameter than the other, so that there 25 are two up-travelling and two down-travelling rows of wick material presented to the transverse draft which is to be humidified thereby. An important feature of my invention 30 is continuously maintaining such transverse draft by means of a fan of the propeller type that is relatively large and slow-moving. Hence, vibration, noise and violent drafts are avoided, while continuous efficient operation is assured.

An electric motor suitably mounted, preferably within the casing of the apparatus, drives a countershaft, through a worm gear whereby the countershaft has relatively slow speed, and the slow speed fan is driven from

this shaft. This countershaft also drives one or both of the wick supporting shafts through a second worm gear whereby a yet lower speed, as low as may be desired, can be predetermined for the travel of the wicks upward

45 from and downward into the water in the reservoir.

In order to be of any real utility, apparatus of this type must be operated so as to efficiently evaporate surprisingly large amounts 50 of the water, and I have discovered that as a

result of the evaporation, the water in the reservoir will become overloaded with natural mineral salts, dust and other non-volatile matter, to such an extent as to clog and greatly impair the efficiency of the evaporating 55 surface afforded by the wick bands. To avoid this, and also to provide for frequent refillings that are necessary, the reservoir is equipped with a float-controlled inlet cock, whereby the water is automatically maintained at the desired level and, in combination 60 with such automatic supply, there is also an overflow waste pipe, the two being so designed that when the cock operates it supplies a substantial overplus of water which runs off through the waste pipe and so keeps the reservoir water as clean and pure as may be desired.

The apparatus is peculiarly adapted for location adjacent the end of a radiator, but 70 substantially out of contact therewith. In this situation, the air is drawn into the fan by inflow which tends to be along radial lines of a hemisphere, the radius of which depends on the size of the fan. Hence, a large fan 75 will be quite effective for drawing in a large part of the heated air, when the radiator is hot; if the heat be turned off the radiator, the air in the room is just as accessible to the fan as it was before. This is an entirely novel 80 arrangement, so far as I am aware. In prior devices where the hot draft has been supplied through a register from a hot air furnace, closing the register results in stopping the draft, thereby discontinuing the humidifying 85 operation and where motors have been used, they have not been arranged in effective draft inducing relation to a radiator or other heater.

The above and other features of my invention 90 may be more fully understood from the following description, in connection with the accompanying drawing, in which

The figure is a partly schematic view, showing the humidifier in vertical section, in operating relation to a radiator in elevation, a humidostat and operating circuits being 95 schematically indicated.

In this drawing, the humidifier, A, is close 100 to but spaced apart from the end of the radi-

ator indicated at B. If desired, a humido-stat, C, controls flow of electrical current from one side of a line, a, through a lead, b, c, d and a return, e, which furnishes the power for driving the operating motor described below. An adjustable rheostat, R, may be added for manual control to determine the normal maximum speed for the motor.

10 While the details of the humidifier, A, may be varied within wide limits, I prefer to assemble the parts in an exterior casing, which may be of sheet metal comprising upright side members, 1, a top, 2, and a rear wall, 3, having a relatively large opening, 4, through which air may be drawn by the fan, 5, which is preferably surrounded by converging walls, 6, 6, the exit portion of which, at 7, is preferably approximately the same diameter as the fan, whereby the draft propelled in the direction of the arrows results in establishing suction over the inlet 4, which is shown as of substantially larger diameter than the fan. In the bottom of the casing is formed a tank, 8, in which discharges a supply cock, 9, connected by pipe, 10, with the usual water supply system. Turning off operation of the cock to maintain a desired level of water in the reservoir, is conventionally indicated as being by means of a lever, 11, controlled by a float, 12. The level is further controlled by the overflow pipe, 13, which extends through the bottom of the reservoir as a waste pipe, 14, which may be carried outdoors or connected to any suitable drainage system.

15 In the reservoir 8, is rotatably supported a shaft, 15, carrying sets of relatively large pulleys, 16, and smaller pulleys, 17. In the upper part of the casing, also rotatably mounted, is a similar shaft, 15a, carrying a set of larger pulleys, 16a and a smaller set of pulleys, 17a. Each pair of larger pulleys, 16, 16a, has fitted thereon a belt, 18, which is preferably a cylindrical endless band of wick material, while each pair of the smaller pulleys, 17, 17a, carries a similar belt, 19. I thus provide across the front of the apparatus, four rows of wicks in staggered relation, and the number of wicks in each row will depend on the number of pulleys, which may be as few or many as may be desired.

20 The belts may be driven at the desired low speed and the fan at any desired higher speed, in any suitable way. Preferably, however, the fan, 5, is keyed to a shaft, 20, rotatably mounted in a bearing, 21, carried by a spider, 22, which may be secured to the wall, 6, in any desired way as by spot welding or riveting. The forward end of shaft 20 is driven through beveled gears, 23, the driving gear being mounted on countershaft, 24, supported in brackets 25, 26. This countershaft, 24, also carries a worm, 27, meshing with a worm gear, 28, which drives the shaft 15a,

thereby rotating all of the pulleys, 16a, 17a and, through the wick bands 18, 19, driving the lower pulleys, 16, 17.

25 The countershaft, 24, has rigid thereon a worm wheel, 29, driven by worm, 30, on the armature shaft, 31, of an electric motor, 32.

30 From the above, the operation of the device will be obvious. The water supply, drain pipe and electric circuit being connected up, the weight of the float 12, in the empty tank 8 will cause opening of the cock, 9, until the rising water lifts the float and closes the valve, the apparatus being proportioned so that the outlet of the overflow pipe, 13, will be below the level of the water so as to be draining off substantial quantities thereof. It will be obvious to those familiar with apparatus of this kind, that there is a range of water level sufficient to permit this. Even in carefully designed apparatus, the valve affords sufficient resistance to operation so that the water level must fall considerably below normal before the float 12 will have sufficient excess weight to open the valve, and it must also rise considerably above normal before the float will have enough excess floatation to close the valve. Then, if the capacity of overflow pipe 13 is sufficient smaller than the capacity of the supply, said overflow pipe may be substantially submerged before the float closes the valve and thereafter draining off of the water to the level of the overflow will not be sufficient to cause operation of the float by gravity. The current then being turned on to drive motor 32 the countershaft, 24, will be driven through 29, 30, at the right speed for operating the fan, 5, through gears 23. By reason of the reducing gear, the fan will be driven at much lower speed than in the ordinary case, where the fan is mounted directly on the armature shaft of the motor. Consequently, the fan will be relatively noiseless and the draft, a breeze as gentle as may be desired. As the rate of evaporation of the water will depend in an important degree upon the speed of the fan, the gearing of the wick drive shaft, 15a, through the reducing worm, 27, and worm gear, 28, is of advantage as making these speeds interdependent.

35 Moreover, the speed of the wicks may be as slow as desired. This is an important feature because it is desirable to give the wicks time to lose part of their wetness, so as to expose the relatively great evaporating area afforded by fibers and pores of the wicking, which are more or less sealed when the wicks are soaking wet. I prefer to have the wicks travel upward in the rows adjacent the fan where the air is driest and has greatest affinity for the water. The down travelling rows subsequently encountered by the partly moistened air will have a desired higher efficiency for further saturation of the air by reason of the fact that the excess water has

been then removed sufficiently to expose a maximum area of wet fiber, to the draft.

The arrangement shown has the advantage that above and below the converging wall, 6, 5 the casing not only affords housing for the moving parts and for the reservoir, but also affords eddy spaces in which the air circulates more slowly than in the draft, affording further opportunity for the upper and lower 10 portions of the wick belts and also for the surface of the water in the reservoir, to moisten the air. In this connection, it will be understood that the straight, horizontal arrows are merely indicative of the main draft, no attempt having been made to show the spreading or eddying of this draft which necessarily results from injector action and vacuum 15 tendency where the back of the casing is closed in and the front is wide open, as in the present case. Also, no attempt is made to show the natural upward draft which is so 20 universally known as characterizing operation of all steam and hot water radiators and it will be obvious that the laterally presented 25 inlet to the fan is merely in non-positive or inductive relation to such draft, taking only so much as the fan is able to suck in laterally therefrom.

I claim:

30 1. A humidifying apparatus adapted to be placed in inductive relation to a draft producing air heater and including a casing, a fan for moving air through the casing, a water reservoir in the lower portion of said 35 casing, a plurality of separate belts of absorbent material arranged to afford free paths for flow of air between them and means for supporting them for vertical travel upward from and downward into 40 water in said reservoir and in the path of said draft from the fan, said supporting means, including cooperating rotary supports for said belts, at least one of which is positively rotated; and means for operating said fan 45 and said belts at widely different but interdependent speeds, including a rotary electric motor, a shaft driven thereby through a reducing gear, gearing between the shaft and the fan designed for proper speed of the 50 fan, and a worm on the shaft cooperating with the worm gear to drive said belts at correspondingly reduced speed.

2. A humidifying apparatus adapted to be placed in inductive relation to a draft 55 inducing air heater and including a casing, a fan for moving air through the casing, said heater, a water reservoir in the lower portion of said casing, a plurality of separate belts of absorbent material and means for supporting them for vertical travel upward 60 from and downward into water in said reservoir, in staggered alternate relation, including cooperating rotary supports for said belts, at least one of which is positively rotated; and means for operating said fan and

said belts at widely different but interdependent speeds.

3. Humidifying apparatus, including a water reservoir, float-controlled, intermittently operating means for over-supplying water to the reservoir when the level falls and an overflow drain pipe designed and operating to cause said overflow to become deeply submerged before the float shuts off the supply thereby causing substantial drainage of 75 water through the overflow when the supply operates, upwardly extending belts of absorbent material and means for continuously rotating them at slow speed, and a fan and means for operating it to create circulation of air impinging among and around said belts.

4. An air heater arranged to create and facilitate an induced upward draft of heated air in a room to be heated, in combination with a fan having an air intake laterally applied in inductive relation to suck in part of said draft, without preventing said upward draft, and means for maintaining water in the evaporative relation to the outlet 80 draft of said fan.

Signed at New York in the county of New York, and State of New York, this 25th day of May, A. D. 1926.
